8 Claims. (Cl. 68—5)

This invention relates to the treatment of textile materials with gaseous media, and more particularly to an apparatus for steaming textile material, such as fibers and fiber aggregates.

It is common practice to expose textile material, such as fibers and fiber aggregates, to live steam in order to impart desired chemical or mechanical properties to the textile material. Known commercial devices for steaming fibrous textile material are limited to batch operation because of the difficulties inherent in effectively sealing a steam chamber at the inlet and outlet openings for continuously supplied and withdrawn loose fibers.

The primary object of this invention is the provision of a steaming arrangement for fibrous textile materials, which permits treatment of the material while it travels through a steam chamber in continuous flow.

Another object is a steaming arrangement in which loss of steam is practically completely avoided.

Yet another object is the steaming of combed wool and of similar materials without mechanical damage to the fibrous material.

With these and other objects in view, the invention in one of its aspects provides a container having an inlet and an outlet portion and equipped to have steam admitted thereto. A strand of a continuous chain extends in the container from the inlet portion to the outlet portion, and is driven in a direction toward the outlet portion by suitable drive means at a certain linear speed. At the inlet portion, the chain passes through a mechanical seal which includes a partition plate fixedly secured to the container and formed with two openings passing therethrough in a direction transverse of the direction of chain movement. The two openings are spaced from each other in a third direction which is transverse of the aforementioned two directions. The plate also has a bore arranged between the two openings and extending in the direction of movement of the chain. The chain passes through the bore. The seal further includes two rollers. Each roller has two axially terminal portions arranged on opposite sides of the partition plate, and a central portion of smaller cross section rotatably received in a respective bore of the partition plate. Drive means are provided for rotating the rollers at a circumferential speed of the terminal portions, which is substantially greater than the linear speed of the chain.

Other features and many of the attendant advantages of this invention will be readily appreciated as the same becomes better understood by reference to the following detailed description, when considered in connection with the accompanying drawing, the sole figure of which shows the essential working elements of a steaming arrangement of the invention in a perspective fragmentary view.

There is shown a tubular container 1 of rectangular cross section. The internal wall of container 1 is provided with a lining which helps the guiding progression of the textile material moved upwardly of the container. An endless chain 2 is arranged in such a manner that one strand of the chain passes axially through the container 1 whereas the other strand moves outside the container. The chain portion within the container 1 moves from the left to the right, as viewed in the drawing, that

2

is, from an inlet portion to an outlet portion of the tubular container.

A portion of the container intermediate the inlet and outlet portions has perforations 6 therethrough and is spacedly enveloped by a casing 3. A source of steam communicating with the casing is partly indicated by a flanged steam supply pipe 3a. Condensate and excess steam are exhausted from the casing 3 through a pipe 3b. The outlet end of the casing is closed by a flange 3c through which the outlet portion 3d of the container 1 passes. The inlet end of the casing will be understood to be equipped with a similar flange which has been omitted from the drawing, together with portions of the casing 3 and the container 1, so as better to show details of a mechanical seal 4 in the inlet portion of the container 1.

The seal includes a partition plate 7 parallel to the container axis. A front portion of the plate is bounded by two parallel flat faces parallel to the container axis. The two faces approach each other in the direction of chain travel so that the trailing edge portion 8 of the partition plate is wedge shaped. The chain 2 passes through a bore 9 in the plate 7, and leaves the bore through an exit orifice in the trailing edge portion 8.

The plate 7 has two transverse horizontal openings therethrough on opposite sides of the bore 9. The openings provide bearings for respective rollers 4a, 4b. Each roller has two terminal axial portions of relatively large diameter adjacent one of the faces of the plate 7, and a central portion of smaller diameter rotatably received in an opening of the plate 7. It will be understood that the radial end faces of the rollers 4a, 4b sealingly engage corresponding opposite walls of the container 1, and that further sealing connection is provided between the top and bottom walls of the container 1 and the cylindrical surfaces of the axially terminal portions of the rollers.

The chain 2 has alternating links 10 which extend in a common horizontal plane during the movement of the chain through the container 1, and links 11 which extend in a common vertical plane. The vertical links are equipped with horizontally projecting studs 11a.

During its outward movement from the container 1, the chain 2 passes through a sealing device 5 mounted on the flange 3c. It includes two shutter flaps 12, 13 attached to the open end of the outlet portion 3d by respective pivot pins 14, 15. The position of the flaps 12, 13 is controlled by a pneumatic actuator connected to the flaps by a tubular rack 16 simultaneously meshing with two segment gears 17 respectively fastened to the pivot pins 14, 15. Only one segment gear is visible in the drawing.

The rack 16 is attached to a piston 18 in a cylinder 19. The piston divides the cylinder cavity into two compartments. The rack 16 is mounted in a stuffing box 16a for movement inwardly and outwardly of the casing 3. The axial bore of the rack has respective orifices in the casing 3 and in the compartment of the cylinder 19 remote from the casing 3. The other cylinder compartment is vented to the atmosphere in a manner not further illustrated.

The rollers 4a, 4b are rotated in opposite directions by an electric motor 20 through a gear box 21 in such a manner that the opposite cylindrical face portions of the rollers travel inwardly of the container 1. Linear movement of the chain 2 through the container is actuated by a motor 22 equipped with a reduction gear 23 (not shown in detail) and driving a sprocket 22'. The chain 2 is also trained over an idler 23'. The motors 20 and 22 are respectively connected by conductors 24 and 25 to a common control box 26.

The aforescribed apparatus is operated as follows: The two separate drive systems are coordinated in such a manner that the linear speed of the chain 2 is only a fraction of the circumferential speed of the exposed cylindrical surfaces of the rollers 4a, 4b. Combed wool or similar loose textile material supplied to the inlet end of the container 1 therefore is gripped by the rollers and moved inwardly of the container at a higher speed than that of the chain. Because of its configuration, the chain engages the fibrous material and holds it back. The material passes between the rollers 4a, 4b which may be movable toward and away from each other, and urged into engagement by springs in a conventional manner not further illustrated, and is then released by the rollers. Further movement of the material toward the outlet end of the container 1 is mainly actuated by the chain 2, and to a smaller extent by the pressure of additional material.

Because of the sudden reversal of the relative speeds of chain and textile material in the inlet portion of the container 1, the material is tightly packed and forms an effective vapor seal. The compacted material is drawn through the remainder of the container 1 by the chain 2 in a manner very similar to the extraction of a bottle stopper by a cork screw. As the material passes the 10 perforations 6, it is exposed to the steam in the casing 3. The pressure of the steam tends to expel the steamed material through the outlet portion 3d. The flaps 12, 13 counteract the expelling force of the steam, the arrangement being such that the effective size of the opening between the flaps, 12, 13 is inversely related to the steam pressure in the casing because of the connection between the outer compartments of the cylinder 19 and the casing. The steamed material is, therefore, further compressed in the outlet portion 3d and forms an effective vapor tight seal.

The interior surfaces of the tubular container 1 should be highly polished to minimize frictional drag and ensuing damage to the material conveyed through the container by the chain 1. Friction between the material and the container walls is not necessary for preventing the escape of steam from the apparatus to the atmosphere.

In its elementary aspects, the drive arrangement for the rollers 4a, 4b and for the sprocket 22' may include two synchronous alternating current motors having different rotary speeds, and further modifications of operating speed may be brought about by suitably selecting the transmission ratios of the gear devices 21, 23 or in using a known device to vary the speed instead of gear devices 21, 23. Because of the connection of the motors to a common source of alternating current, the desired speed difference between the rollers and the chain is readily maintained.

It is preferred, however, to use direct current variable speed motors 20, 22 and to interconnect them in such a manner by conventional electronic controls that the motor speeds may be varied as needed while the difference or ratio of the individual motor speeds is held at a fixed value. The necessary control circuits are known, and not in themselves relevant to this invention. The control apparatus is thus illustrated merely by the box 26 in which it is enclosed.

It should be understood, of course, that the foregoing disclosure relates only to a preferred embodiment of the invention, and that it is intended to cover all changes and modifications of the example of the invention herein chosen for the purpose of the disclosure which do not constitute departures from the spirit and scope of the invention set forth in the appended claims.

What is claimed is:

1. A steaming arrangement for textile material comprising, in combination:

(a) a container having an inlet portion and an outlet portion;

(b) means for admitting steam to said container;

5 (c) a continuous chain member, a portion of said chain member extending in said container from said inlet portion to said outlet portion;

(d) first drive means for continuously moving said chain member in said container in a direction from said inlet portion to said outlet portion at a predetermined speed;

(e) sealing means in said inlet portion, said sealing means comprising

(1) a partition member fixedly secured to said container and formed with two openings therethrough transverse of the direction of movement of said chain member, said openings being spaced from each other transversely of said direction of movement, and with a bore extending in said direction of movement intermediate said openings, said chain member being received in said bore for passage therethrough, and

(2) two roller members arranged for rotation about respective substantially parallel spaced axes, each roller member having two axially terminal portions and a central axial portion of smaller cross section than the cross sections of the corresponding terminal portions, said central portions being respectively received in said openings for rotation about said axes; and

(f) second drive means for rotating said roller members at a circumferential speed of the terminal portions thereof which is substantially greater than said predetermined speed.

2. An arrangement as set forth in claim 1, further comprising sealing means in said outlet portion, said chain passing through the last mentioned sealing means.

3. An arrangement as set forth in claim 1, further comprising connecting means connecting said first and second drive means for maintaining a predetermined difference between said circumferential speed and said predetermined speed.

4. An arrangement as set forth in claim 1, wherein a portion of said container is formed with a plurality of perforations therein, and said means for admitting steam include a casing member spacedly enveloping said container portion, and a source of steam communicating with said casing.

45 5. An arrangement as set forth in claim 1, wherein said chain member is elongated and is composed of a plurality of longitudinally consecutive link members, said link members being flat, and each link member extending in a longitudinal plane angularly offset from the plane of an adjacent link member.

6. An arrangement as set forth in claim 5, further comprising stud means projecting from said link members transversely of the direction of elongation of said chain member.

55 7. An arrangement as set forth in claim 1, wherein said partition member has two opposite faces spaced in the direction of the axes of said roller members, said faces converging in said direction of movement to define a wedge-shaped trailing edge portion of said partition member, said bore having an orifice in said edge portion.

8. A steaming arrangement for textile material comprising, in combination:

(a) a tubular container having an axis, an inlet portion and an outlet portion axially spaced from said inlet portion, and a portion intermediate said inlet and outlet portions formed with a plurality of perforations therethrough;

(b) a casing spacedly enveloping said intermediate container portion;

(c) a conduit communicating with said casing for admitting steam thereto;

(d) a continuous chain, a portion of said chain being outside said container, and another portion axially extending in said container between said inlet and outlet portions;

- (e) first drive means for continuously moving said chain in said container in a direction from said inlet portion toward said outlet portion;
- (f) sealing means at said inlet portion, said sealing means including
  - (1) a partition member fixedly secured in said container and having two opposite major faces, said faces having respective portions substantially parallel to each other and to the direction of movement of said chain and respective other portions converging in said direction of movement and jointly defining a wedge-shaped trailing edge portion of said partition member,
  - (2) said partition member being formed with two spaced openings therethrough connecting said parallel face portions, and with a bore intermediate said face portions and substantially parallel thereto, said bore having an orifice in said trailing edge portion, said chain being movably received in said bore, and
  - (3) two roller members, each roller member having two axially terminal portions and a central

5

15

20

portion of smaller cross section than the cross sections of the corresponding terminal portions, each central portion being rotatably received in a respective one of said openings;

(f) second drive means for rotating said roller members about the respective axes thereof; and

(g) speed control means connected to said first and second drive means for controlling rotation of said roller members at a circumferential speed of said terminal portions thereof which is substantially greater than the linear speed of said chain.
